UNITED STATES PATENT OFFICE

JOHN R. ELGAN, OF LOS ANGELES, CALIFORNIA

DESIGN FOR A PRINTER'S WEDDING STATIONERY BLANK

Application filed April 14, 1930. Serial No. 35,249. Term of patent 14 years.

To all whom it may concern:

Be it known that I, JOHN R. ELGAN, a citizen of the United States, residing at Los Angeles, in the county of Los Angeles, State of California, have invented a new, original, and ornamental Design for a Printer's Wedding Stationery Blank, of which the following is a specification, reference being had to the accompanying drawing, forming part thereof.

The figure is a plan view of a blank adapted for use in the over-printing or over-engraving of wedding announcements or invitations thereupon.

The characteristic feature of my design resides in the relatively faint or delicately tinted representation of a bridal bouquet on a wedding stationery blank.

What I claim is:

The ornamental design for a printer's wedding stationery blank, as shown and described.

In testimony whereof, I have hereunto set my hand at Los Angeles, California, this 12th day of April, 1930.

JOHN R. ELGAN.
